UNITED STATES PATENT OFFICE

154,205

DESIGN FOR A RING COMB

Stella Kovacs and Dorman J. Fulkerson, Dearborn, Mich., assignors to Paragon Products Company, Detroit, Mich., a corporation of Michigan

Application April 30, 1948, Serial No. 146,078

Term of patent 14 years

(Cl. D86—8)

To all whom it may concern:

Be it known that Stella Kovacs and Dorman J. Fulkerson, citizens of the United States of America and residents of Dearborn, in the county of Wayne and State of Michigan, have invented a certain new, original, and ornamental Design for a Ring Comb, of which the following is a specification, reference being had to the accompanying drawing, forming a part thereof, wherein:

Fig. 1 is an elevational view of a ring comb embodying our new design;

Fig. 2 is a perspective view thereof;

Fig. 3 is a side elevational view thereof; and

Fig. 4 is a sectional view taken along the line 4—4 of Fig. 1.

We claim:

The ornamental design for a ring comb, substantially as shown.

STELLA KOVACS.

DORMAN J. FULKERSON.
